UNITED STATES PATENT OFFICE.

HENRY C. STAMM, OF MECHANICSBURG, PENNSYLVANIA.

WASHING-MACHINE.

1,133,890.

Specification of Letters Patent. Patented Mar. 30, 1915.

Application filed September 28, 1914. Serial No. 863,955.

To all whom it may concern:

Be it known that I, HENRY C. STAMM, a citizen of the United States of America, residing at Mechanicsburg, in the county of 5 Cumberland and State of Pennsylvania, have invented certain new and useful Improvements in Washing-Machines, of which the following is a specification, reference being had therein to the accompanying 10 drawing.

This invention relates to certain new and useful improvements in washing machines and more particularly to that class of machines known as pounders; the object being 15 to provide a machine in which a supplemental tub is mounted upon spring supports to receive the clothes to be washed, which are engaged by a series of vacuum cups carried by a plunger in such a manner that 20 the clothes will be lifted on the up-stroke of the plunger by the vacuum cups so as to cause the water to circulate through the clothes.

Another object of the invention is to provide 25 novel means for reciprocating the plunger whereby the plunger can be adjusted according to the amount of clothes within the clothes receptacle so that all danger of the mechanism becoming broken when in operation, is prevented.

Another object of my invention is to provide 30 a washing machine with a false bottom under which is arranged an inlet having a steam and an air pipe connected thereto by means of which, steam or air can be fed into the washing machine so as to aid the washing action of the machine.

Another object of the invention is to provide 35 a yielding plunger to reduce the jar on the driving mechanism.

Other and further objects and advantages of the invention will be hereinafter set forth and the novel features thereof defined by the appended claims.

45 In the drawings—Figure 1, is a vertical section through my improved construction of washing machine, showing the driving mechanism in elevation; and Fig. 2, is a detail section through one of the vacuum 50 cups.

Like numerals of reference refer to like parts in the several figures of the drawings.

In carrying out my invention, I employ a cylindrical receptacle 1 mounted upon suitable legs 2 in which is arranged a perforated 55 false bottom 3 slightly spaced from

the bottom of the receptacle 1 on which is mounted a number of coil springs 4 forming a yielding support for a supplemental receptacle 5 which is cylindrical in shape 60 and is arranged concentric with the outer receptacle 1 and is provided with a perforated bottom 6.

The main or outer receptacle 1 is provided with an outlet pipe 7 forming a drain 65 therefor which is controlled by a valve 8 and the bottom of the main receptacle is provided with an inlet T 9, to one branch of which is connected a steam or air pipe 10 provided with a valve 11 controlling the 70 flow of steam and air therethrough; the other branch of the T being provided with a water inlet 12 provided with a valve 13 through which water is adapted to pass into the receptacle. 75

In operation, the water and steam are admitted to the receptacle 1, of course, being understood that a suitable detergent is employed to form suds for washing purposes, and when the clothes are in position within 80 the inner receptacle 5, they will be held submerged within the washing fluid so that they can be readily acted upon by the pounder, as will be later described.

Extending out from opposite sides of the 85 outer receptacle 1 are spaced arms 14 and 14' the tub being also provided with tubular guides 15 in which are mounted rods 16 and 17 which are connected at their upper ends to a cross bar 18, said cross bar being provided with sockets 19 at its ends to receive the rods 16 and 17 in which said rods are secured by set nuts 20, as clearly shown, in order to allow the cross bar to be detached when desired. 95

Adjustably mounted on the rods 16 and 17 between the respective arms are sleeves 21 provided with stud pins 22 to which are pivotally connected pitman rods 23 which are connected at their opposite ends to wrist 100 pins 24 secured to drive wheels 25 mounted upon a drive shaft 26 mounted in suitable bearings 27 extending from the bottom of the receptacle 1; said drive shaft being provided with a drive pulley 28 which is adapted to be driven by a belt from the power shaft. It will be seen by this construction that when the drive shaft 26 is revolved, the cross bar 18 will be reciprocated through the pitman rods and guide rods. 105

The bar 18 is provided with a centrally threaded bearing 29 in which is mounted 110

2

the threaded upper end 30 of a plunger 31, said plunger rod being provided with a hand wheel 32 for revolving the same in order to adjust the plunger rod within the 5 bearing.

The lower end of the plunger rod extends into a sleeve 33 which is provided with a head 34 fitting snugly within the inner receptacle 5; said sleeve being provided with oppositely disposed slots 35 through which extends a pin 36 carried by the plunger in order to allow the plunger rod to slide within the sleeve; the plunger rod being surrounded by a coil spring 37 as clearly shown, 10 forming a yielding connection between the plunger rod and plunger head 34 in order to prevent the same from being injured when the same is reciprocated through the driving mechanism. By providing a yielding connection at this point, when a mass of 15 clothes is in position within the inner receptacle, the plunger head 34 is allowed to yield when brought into engagement with the mass, so as to prevent injury to the driving mechanism. The head 34 is adapted to fit snugly within the inner receptacle 5 and is provided with a series of vacuum cups 37 secured to the head by screws or rivets 38 as clearly shown in Fig. 2, said 20 cups being provided with valves 39 so as to allow the washing fluid to pass through the cups on the down-stroke of the plungers and on the up-stroke a partial vacuum is created therein so as to draw the clothes 25 within the inner receptacle, upwardly with the plunger, whereby the clothes are subjected to a pounding action as well as to the agitation caused by the clothes being lifted up and down within the receptacle. 30 From the foregoing description it will be seen that I have provided a washing machine in which the clothes to be washed are supported in a yielding receptacle and are engaged by a yielding plunger so as to prevent 35 injury to the driving mechanism and at the same time to impart an agitative movement thereto. It will also be seen that in rinsing the clothes, air can be injected into the liquid within the receptacle and that by 40 draining the receptacle, the clothes can be wrung.

I claim:

1. A washing machine, comprising a receptacle, guides formed on said receptacle,

guide rods mounted in said guides, a cross bar connecting said guide rods provided with a threaded bore, a plunger rod having a threaded portion working in said threaded bore, means for revolving said plunger rod, a sleeve slidably mounted upon said plunger rod, a spring surrounding said plunger rod between said sleeve and cross bar, a head carried by said sleeve, and means for reciprocating said guide rods. 60

2. In a washing machine, the combination with a receptacle, of a guide rod mounted to each side of said receptacle, a cross bar having a centrally threaded bore, a plunger rod provided with a threaded portion working in said bore, a hand-wheel carried by said plunger rod for revolving said plunger rod within said bore to adjust the position thereof, a head slidably carried by said plunger rod, and means for reciprocating said guide rods.

3. In a washing machine, the combination with a receptacle, of spaced arms projecting outwardly therefrom provided with tubular guides, rods slidably mounted in said guides, a cross bar connecting the upper ends of said rods, an inner receptacle arranged within the first-mentioned receptacle, a plunger arranged within said inner receptacle, and a plunger rod yieldingly connected to said plunger having a threaded portion mounted in the threaded bore of said cross bar, means for turning said plunger rod within the bore of said cross bar for adjusting the position of said plunger within the inner receptacle, and means for reciprocating said rods. 90

4. A washing machine, comprising an outer receptacle having a false bottom, an inner receptacle supported within said outer receptacle, a plunger working within said inner receptacle, a plunger rod having a slideable connection with said plunger, a cross bar in which said plunger rod is adjustably mounted, and means for reciprocating said cross bar.

In testimony whereof I hereunto affix my
signature in the presence of two witnesses.

HENRY C. STAMM.
